UNITED STATES PATENT OFFICE.

BENJAMIN STRUMP, OF BROOKLYN, NEW YORK.

SAFETY CARD CASING.

Application filed March 3, 1927. Serial No. 172,242.

My invention relates to safety card casings of the kind adapted for general use but especially suitable for service in taxicabs, for displaying cards, charts, license tickets and the like, while preventing direct access to such article.

More particularly stated I provide a small flat casing in the form of a box and having a lid, these parts being adapted to be locked together so as to prevent the lid from being opened, the locking mechanism being so located, constructed and arranged as to increase the efficiency of the device as a whole, and to increase the difficulty of unauthorized persons tinkering with the contents of the casing.

Reference is made to the accompanying drawing forming a part of this specification, and in which like reference characters indicate like parts throughout the several figures.

Figure 1 is a front elevation of my improved safety card casing, here shown as closed, certain parts being broken away.

Figure 2 is a section on the line 2—2 of Figure 1, looking in the direction indicated by the arrows.

Figure 3 is a plan view of the casing considered as an article of manufacture, and here shown as open and empty.

Figure 4 is a plan view of the device considered as an article of manufacture, the casing being closed.

Figure 5 is a section on the line 5—5 of Figure 1, looking in the direction indicated by the arrows.

The body portion of the casing appears at 6, and is essentially a flat, box-like member. This body portion is made of sheet metal, and is provided with a pair of spring tongues 7, 7 integral with it, and preferably made by stamping.

The body portion 6 is further provided with a locking tongue 8 integral with it, this locking tongue carrying an edge wall 9 upon its three edges, as indicated at the bottom of Figure 3.

The body portion 6 is further provided with a pair of retaining ears 10, preferably made of sheet metal.

Connected with the body portion 6 by means of hinges 11, 11 is a lid 12, having substantially the form of a shallow box, and adapted to fit snugly over and around the body portion 6.

The lid 12 is provided with an opening 13,

of relatively large size, as may be understood from Figures 1 and 3.

The lid 12 carries a locking tongue 14, in this instance integral with it, and projecting from its edge, as indicated in the upper portion of Figure 3. This locking tongue 14 carries an edge wall 15, similar in form to the edge wall 9 above described as carried by the locking tongue 8, but having such size that the edge wall 15 can fit snugly over and around the edge wall 9, so as to practically enclose the same.

The parts are so arranged that when the lid 12 is brought down into the position indicated for it in Figure 1, this lid practically encloses the body portion 6, and the locking tongue 14 practically encloses the locking tongue 8.

Mounted within the locking tongue 14 is a lock 16, as indicated more particularly in Figure 2. The lock 16 carries a key barrel 17, which is fitted with a key 18. The lock is in this instance of the Yale type, but this particular form of lock is not essential. The lock is provided with a sliding bolt 19. The locking tongue 8 is provided with a slot 20 extending through its edge wall 9, and the locking tongue 14 is similarly provided with a slot 21, extending through its edge wall 15. The slot 21 is always in registry with the bolt 19, as may be understood from Figures 2 and 3, so that whenever the bolt 19 is thrust outwardly from the lock, it always extends through the slot 21, whether the lid be closed or opened.

The parts are so proportioned and arranged that if the lid be closed, as indicated in Figures 1 and 2, and then the lock 16 be operated so as to thrust the bolt 19 outwardly, this bolt extends through the slot 20 as well as the slot 21. With the parts in the position indicated in Figure 2 and just described, the casing is effectively locked.

The lock 16 is secured firmly within the locking tongue 14 by means of cylindrical rivets 22^a and 23^a, as indicated more particularly in Figure 1.

The body portion 6 of the casing is here shown as containing display cards 24, 25, but the casing may be used for holding and displaying analogous transient members of other kinds, such as license tickets, permit cards of various kind, or in fact any sort of members made of paper or cardboard, of suitable size and form to be displayed.

Located also within the body portion of

the casing, and held in position by the retaining ears 10, is a glass pane 26. This glass pane is preferably made strong and heavy, and may be of plate glass or even 5 glass having a wire netting such as is commonly known in the art.

With the casing lid closed and locked as above described, no person can force the lid open except by breaking the casing to pieces, 10 or at least without making considerable noise and leaving upon the casing all sorts of tell-tale marks.

It often happens that taxicab passengers, inspired by motives of malice or of mischief, 15 seek to tamper with a casing carried by a taxicab, and used for housing cards or other display members of the kind here contemplated.

A taxicab wall is shown at 22, and the casing is held upon it by screws 23.

The operation of my device is as follows:

The various parts of the casing being assembled and arranged as above described, the cards or other display members are fitted 25 into the body portion 6, and held in position by the retaining ears 10. The glass pane 26 is also held in position by these retaining ears, and presses against the cards. The leaf springs 7, carried by the casing 6, press 30 gently against the back side of the cards, and thus hold them flat against the glass pane.

These preliminaries being arranged, the device is locked as above described.

35 I do not limit myself to the precise construction shown, as variation may be made therein without departing from my invention, the scope of which is commensurate with my claims.

40 Having thus described my invention, what I claim as new and desire to secure by Letters Patent, is as follows:

1. In a safety card casing the combination of a hollow body member provided with a locking tongue extending edgewise therefrom, said locking tongue having an edge wall and slot extending through said edge wall, a lid mating said hollow body member and carrying a second locking tongue mating 45 said first mentioned locking tongue, said second mentioned locking tongue having an edge wall and a slot extending through the edge wall, said lid being movable relatively to said body member so as to bring said slots into registry with each other, and a lock carried by one of said locking tongues and provided with a bolt, said lock being so positioned relatively to the locking tongue whereby it is carried as to enable said bolt 55 to be thrust through both of said slots when said slots are in registry.

2. In a safety card casing the combination of a hollow body member provided with a locking tongue extending edgewise therefrom, said locking tongue having an edge 65 wall and a slot extending through said edge wall, a lid mating said hollow body member and carrying a second locking tongue mating said first mentioned locking tongue, said second mentioned locking tongue having an edge wall and a slot extending through the edge wall, said lid being movable relatively to said body member so as to bring said slots into registry with each other, and a lock carried by one of said locking tongues and provided with a bolt which is always in registry with the slot of the same locking tongue which carries the bolt, the parts being so arranged that when said lid is closed 70 both of said slots are in registry with said bolt.

3. In a safety card casing the combination of a hollow body member provided with a locking tongue extending edgewise therefrom, said locking tongue having an edge 75 wall and a slot extending through said edge wall, a lid mating said hollow body member and carrying a second locking tongue mating said first mentioned locking tongue, said second mentioned locking tongue having an edge wall and a slot extending through the edge wall, said lid being movable relatively to said body member so as to bring said slots into registry with each other, one of said tongues carrying a lock provided with a 80 bolt, and the other of said tongues carrying the portion to be engaged by said bolt, in order to lock said hollow body member and said lid together.

4. In a safety card casing the combination 100 of a hollow body member provided with a locking tongue extending edgewise therefrom, said locking tongue having an edge wall and a slot extending through said edge wall, a lid mating said hollow body member 105 and carrying a second locking tongue mating said first mentioned locking tongue, said second mentioned locking tongue having an edge wall and a slot extending through the edge wall said lid being movable relatively to said body member so as to bring said slots into registry with each other, said locking tongues being so formed and so positioned that when said lid is closed one of said locking tongues is partially enclosed within the other, and a lock carried by the locking tongue thus enclosed, said lock being provided with a bolt for engaging the edges of both of said locking tongues.

Signed at New York, in the county of 120 Kings and State of New York.

BENJAMIN STRUMP.
